UNITED STATES PATENT OFFICE.

JOE A. STUBBJARE, OF BILLINGS, MONTANA, ASSIGNOR TO TUBULAR WALL COMPANY, OF BILLINGS, MONTANA, A CORPORATION OF MONTANA.

BUILDING-FORM.

1,230,055.

Specification of Letters Patent. Patented June 12, 1917.

Application filed April 12, 1916, Serial No. 20,803. Renewed April 20, 1917. Serial No. 163,369.

To all whom it may concern:

Be it known that I, Joe A. STUBBJARE, a citizen of the United States, residing at Billings, in the county of Yellowstone, State of Montana, have invented certain new and useful improvements in Building-Forms; and I do hereby declare the following to be a full, clear, and exact description of the invention, such as will enable others skilled in the art to which it appertains to make and use the same.

This invention relates to an improved construction in building forms of the type used in the construction of hollow cement walls.

An object of the invention resides in the provision of a device by means of which hollow cement walls may be formed and wherein provision is made for the extraction of the form after the completion of the wall.

A further object of the invention resides in so constructing the device that after the forms have been removed the members of the wall will be maintained in the same relationship as existed when the forms were in place.

A still further object of the invention resides in the provision of a simple and efficient device of this character, and one wherein the inner portions may be extracted without difficulty.

With these and other objects in view, such as will appear as the description progresses, my invention comprises the combination and arrangement of parts as set forth in and falling within the scope of the appended claims.

Referring to the drawing:

Figure 1 is a side elevation showing a wall being constructed with the use of the forms.

Fig. 2 is a top plan view of the same.

Fig. 3 is a section on line 3—3 of Fig. 1.

Fig. 4 is a section on line 4—4 of Fig. 1.

Fig. 5 is an elevational view looking at the inner face of one of the wall members and showing one of the cross bar spacing supports removed and the other in position.

Fig. 6 is a section on line 6—6 of Fig. 1.

Referring to the drawing wherein like

parts are indicated by like characters throughout the several views:

In Fig. 1 of the drawing the complete wall is illustrated with the forms in place thereon, but this wall has necessarily been made short so as to economize room and therefore but one middle inner form and two end forms are shown, but I wish it to be understood that the number of forms 60 may be increased as the length of the wall is increased.

In Fig. 1 the members of the wall are indicated by the reference character 1, while the outer forms or plates are indicated by 65 the reference character 2. In order that the said members of the wall may be formed by pouring cement within the outer form 2, I have provided a plurality of forms which are designated by the reference characters 70 3, 4 and 5.

The inner form 4 comprises two plates 6 and 7 which have flanges 8 thereon, the edges of the said flanges being arranged in contact so that the said plates 6 and 7 75 together with their flanges 8 will produce a rectangular form with the plates 6 and 7 so arranged that they are parallel to and in spaced relation from the outer form 2.

The end forms 3 and 4 are constructed of 80 two plates 9 and 10 which have flanges 11 thereon, the edges of which flanges contact to produce forms which are of U-shape in cross section. The open ends of these forms, when in use, bear against the ends 12 of 35 the outer form 2.

Thus a space 13 is provided between the outer faces of the plates 6, 7, 9 and 10 of the forms 3, 4 and 5 and the inner face of the outer form 2 so that when cement is 90 poured between the same the members of the wall will be formed, leaving a space 14 between the said members.

In order that these forms 3, 4 and 5 may be maintained in their proper positions and 95 prevented from collapsing during the process of building the wall, I have provided between the plates 6 and 7 of the form 4 and the plates 9 and 10 of the forms 3 and 5 wedge members 15 and 16 which are oppositely arranged so that their contacting cam faces 17 lie in the line of a diagonal of the

rectangle which they form. The action of these wedge members spreads the plates of the forms.

In order that the said plates may be spread to predetermined position before the wall is formed and in order that the wall may be braced after the forms have been removed, I have provided vertically arranged strips 18 adjacent the juncture of each form, which strips bear against the outer faces of the plates of the forms and have cut out portions 19 which are notched, as at 20. In each of these cut out portions is located a strip 21 which extends between the strips 18 on the opposite sides of the forms 3, 4 and 5 and have notches 22 therein which engage with the notches 20 in the said strips 18 so that the strips 21 are prevented from vertical displacement and the spreading action of the plates of the forms limited because of the binding of the strips 18 in the notches 22 of the strips 21. These strips 22 extend between the adjacent flanges of the forms 3 and 5 and the form 4. The length of the cut out portions 19 is greater than the width of the strips 21 for a purpose which will hereinafter appear.

In operation assuming that it is desired to erect a wall of this character the strips 18 are secured in an upright position and the strips 21 placed in the cut out portions 19 so that the notches 22 therein engage with the notches in the said strips 18.

The forms 3, 4 and 5, but it is here understood that any number of the forms 4 that are required because of the length of the wall may be used, are then placed between the strips 21 and 19 so that the flanges on the said forms contact with the said strips 21. One of the wedge members 15 or 16 is then placed within each of the sections 3 and 5 and the other wedge member of each of these pairs is driven downwardly so that its cam face 17 rides on the cam face of the coating wedge so that the plates 9 and 10 of these forms are pushed outwardly to bind against the inner strips 18.

In order that the sections 4 may be likewise spread, I use a plurality of pairs of wedges, the number being determined by the lengths of the said sections. After the forms have been set up in this way the outer forms 2 are put in place and the cement poured between these forms and the forms 3, 4 and 5. After the cement has set the wedges 16 and 17 are withdrawn which allows the plates 6 and 7 of the forms 4 to be withdrawn from their positions and likewise the plates 9 and 10 of the forms 3 and 5. This leaves the strips 21 extending transversely of the wall with the ends thereof embedded in the members of the wall and the strips 18 engaged with these strips 21. These strips 18 are then pulled upwardly

so that the notches 20 are disengaged from the notches 22 in the strips 21, at which time the strips 18 may be moved so that the strips 21 lie without the cut out portions 19 and may then be withdrawn from between the members of the wall. This leaves the strips 21 extending between the members of the said wall and forming brace members to maintain the said wall members in their proper spaced relation.

From the foregoing description it will be seen that I have provided an improved construction for use in constructing hollow cement walls, wherein the inner forms may be removed after the wall has been constructed with little difficult, and I have provided means for holding the inner forms in proper positions previous to the pouring of the cement, which means also acts as braces for the members of the wall after the cement has been poured. I have further so constructed the device that the inner forms will adapt themselves to various widths.

While I have illustrated and described a particular embodiment of my invention, I have merely done so for the sake of convenience and I do not wish to be limited to that particular embodiment as it is obvious that numerous changes may be made in the details of construction thereof without in any way departing from the spirit of the invention or exceeding the scope of the appended claims.

What I claim is:—

1. A wall form comprising outer forms, inner forms arranged in spaced relation to the outer forms, the said inner forms composed of a plurality of sections, means for expanding the sections and means for limiting the spreading movement constructed and arranged to maintain the members of the wall thereafter in spaced relation.

2. A wall form comprising an outer form, inner forms consisting of spaced plates having angularly projecting flanges thereon, the flanges of one plate being constructed and arranged to contact with the flanges of the other plate, means for spreading the said plates, means for limiting the spreading movement of the said plates, the said means consisting of horizontally arranged strips arranged to be embedded in the finished wall, and detachably engaged means for preventing the vertical displacement of the said strips.

3. A wall form comprising an outer form constructed and arranged to control the formation of the outer faces of a poured wall, and means to control the formation of the inner faces of the said wall comprising vertically arranged forms consisting of spaced plates with angularly extending flanges on the edges thereof, the edges of which flanges contact, pairs of wedge mem-

bers arranged between the said plates to spread the same, vertically arranged strips located adjacent the junctures of the forms, said strips having cut out portions in the edges thereof, and notches in the said cut out portions, and transversely arranged strips having notches therein engaging the notches in the vertical strips and constructed and arranged to prevent the transverse dis-

placement of the first mentioned strips and thereafter brace the members of the wall.

In testimony whereof, I affix my signature, in the presence of two witnesses.

JOE A. STUBKJARE.
